MACHINE FOR POPPING POPCORN AND
VENDING THE SAME

Louis K. Obdyke, Glendale, Calif.

Application December 29, 1937, Serial No. 183,634

5 Claims. (CL. 53—4)

This invention relates to an automatic vending machine, and particularly pertains to a machine for popping popcorn and vending the same.

Heretofore various types of popcorn popping and vending machines have been made. It is of prime importance in machines of this type that the popcorn be popped rapidly and that the quantity of grains being heated at any one time shall be thoroughly popped. This requires a controlled application of heat, as well as means for introducing a determined quantity of corn into the popping receptacle and for emptying the popped corn from the receptacle after proper popping interval has taken place. One of the objections to machines of this type has been that since the popcorn is bought by the individual, who initiates operation and waits until the corn is popped, it is necessary to pop the corn in the shortest possible interval of time. In doing this an extreme heating temperature is required and this sometimes results in the accidental ignition of the corn producing a serious fire hazard. If on the other hand a proper high temperature is not provided the corn may not be thoroughly popped, or will require such a long popping interval as to prejudice prospective customers against using the machine.

It is the principal object of the present invention to provide a machine for automatically popping and dispensing popcorn within which a determined quantity of corn may be disposed in a popping receptacle and which receptacle is disposed in proximity to a heating element adapted to heat a liquid heating medium within which the corn is popped thereby insuring the development of a maximum amount of heating for the popping operation and eliminating the fire hazard attendant thereto. It is a further object of the present invention to provide novel means for supplying and maintaining a quantity of liquid heating medium in association with the heating element, to supply a condiment to the popped corn and to discharge the corn from the popping receptacle by an automatic operation when it has been popped.

Another object of the present invention is to provide a suitable wiring arrangement including automatic switch controls for the heating element and the driving motor and thermostat controls to establish and maintain a desired temperature in the liquid heating medium.

The invention is illustrated by way of example in the accompanying drawings, in which:

55 Figure 1 is a view in perspective showing the

complete machine with which the present invention is concerned.

Fig. 2 is a view in vertical section through the machine showing the parts in elevation and with the side of the machine removed.

Fig. 3 is a view in plan through the preferred form of the invention as seen on the line 3—3 of Fig. 2.

Fig. 4 is a view in central vertical section through the machine as seen on the line 4—4 10 of Fig. 3.

Fig. 5 is a view in vertical section showing the pump mechanism and the manner in which liquid level is maintained within the heating pan.

Fig. 6 is a view showing the popping receptacle 15 in a tilted position and indicating the manner in which the oil draining from the floor of the receptacle is directed back into the heating pan.

Fig. 7 is a view in plan with parts broken away showing a modified form of the invention in 20 which a perforate floor is provided for the popping receptacle.

Fig. 8 is a fragmentary view in section and side elevation as seen on the line 8—8 of Fig. 10 showing the coin control switch with parts in solid lines indicating the open position of the switch and parts in dotted lines indicating an intermediate position partially closing the switch.

Fig. 9 is a view similar to Fig. 8 showing the switch in closed position.

Fig. 10 is a view in section and elevation as seen on the line 10—10 of Fig. 9 showing the switch mechanism.

Fig. 11 is a view showing the wiring diagram of the machine including an electric thermostat 35 temperature control.

Fig. 12 is a view showing the wiring diagram of the machine showing a fluid expansion temperature control.

Referring more particularly to the drawings, 40 18 indicates a main frame comprising a plurality of lower horizontal frame elements 11, and upper frame elements 12 connected at their corners by frame posts 13 and cross connected by horizontal elements 14. Suitable cover panels 15 are supported by these elements to provide a closure for the operating mechanism of the device. These panels are preferably formed with windows 16 and carry a top 17 there-above. At a point intermediate the top and bottom elements 11 and 12 50 are horizontal elements 18 for supporting a floor 19. Upon this floor the main units of the present invention are mounted. The structure includes a heating unit 20, a popping receptacle 21, a synchronized driving unit 22 and a motor 23. 55

Mounted in the top 17 of the structure is a popping corn receptacle 24, and disposed beneath the floor 19 is a reservoir 25 containing popping oil and means to pump this oil.

5 Referring particularly to Figs. 2 and 4 of the drawings it will be seen that an insulated base 26 is mounted on the floor 19 and serves as a support for electric heating elements 27. These elements may be disposed in any desired arrangement, but are preferably disposed parallel to each other and are positioned in a common horizontal plane. Electric conduits 28 and 29 are attached to these heating elements to supply current therefor in a manner to be hereinafter described.

15 15 Mounted in heating exchange relationship to the heating elements 27 is a heating pan 30. This is a shallow pan preferably rectangular in shape and extending with its marginal length lengthwise of the machine. Popping liquid is intended 20 to be used in said pan and is delivered from the popping oil reservoir unit 25 as will be hereinafter described. Tiltably mounted with relation to the pan is the corn popping receptacle 21 which is formed with opposite side walls 32 and a vertical 25 back wall 33. A top wall 34 is provided to prevent the corn from popping over the top of the receptacle and into improper parts of the machine. The bottom of the receptacle is formed with a perforate floor 35 which under normal conditions 30 will be submerged within the heating pan 30. It is found preferable to make the floor 35 from reticulated materials. The forward end of the receptacle is open and extends between side walls 36. These walls form the opposite sides of a 35 downwardly extending shute 37 which communicates with an outwardly and downwardly inclined discharge shute 38. The discharge shute 38 extends through the front wall 15 of the housing for the machine and is normally covered by a door 39 which is hinged upon a horizontally disposed hinge at its upper edge. The popping receptacle 21 is mounted upon arms 40. The arms are fixed to the side walls 32 of the receptacle and have downwardly and forwardly extending portions 41 40 which are engaged by a horizontal pivot rod 42 carried by fixed brackets 43. Brackets 43 are suitably attached to the insulating block 26 or to the floor 19. An extending lever end 44 forms a continuation of one of the arms 40 and is engaged by an operating rod 45 actuated by mechanism to be hereinafter described. A vertical bracket 46 is fixed adjacent to the rear end of the receptacle and carries a horizontally reciprocating vibrating rod 48. This rod engages a wear 45 surface 49 mounted upon the back wall 33 of the receptacle and through which a vibrating motion is imparted to the popping receptacle during the popping operation. The vibrating rod 48 is actuated by an element of the power transmission 50 unit 22 as will be hereinafter described. The top wall 34 of the popping receptacle has an inclined opened mouth 50 which is in filling register with a spout 51 leading from a valve housing 52. The valve housing 52 rotatably supports a valve element 53 which is formed with a slotted opening 54 normally in alignment with a draw-off shute 55 leading from the popping corn receptacle 24. A vertical plate 56 is adjustably mounted upon a screw 57 and may be used to control the width 55 of a throat 58 through which the popping corn may flow from the receptacle 24 into the valve 53. The valve is rotatably supported upon end trunnions 54', one of which carries an operating lever 55'. This lever is connected with a pitman rod 59 which is driven from the power transmission

unit 22 in a manner to be hereinafter described. The spout 51 is fitted with a safety shutter 60 which is carried upon a pivot 61 mounted on a bracket 62 of the spout. A lever 63 is connected with the member 60 and extends downwardly 5 where it terminates in a support for a roller 64 which engages the back wall of the receptacle 21. A horizontal extension of the lever 63 forms an arm 65 carrying a counterweight 66. The counterweight tends to swing the gate 60 closed when the receptacle 21 is in a tilted position and when it is out of engagement with the roller 64 carried by the lever.

The synchronized power unit 22 comprises a main frame 67 having vertical portions 68 and 69 spaced from each other to form bearing supports for the various shafts to be hereinafter described. The motor 23 is provided with a reduction gear unit 70 which drives a shaft 71. The shaft 71 extends horizontally and is rotatably supported in the members 68 and 69 of the frame. Mounted upon the shaft 71 is a worm gear 72 and a cam 73 which engages the end of the rod 48 and vibrates it. The worm gear 72 drives a worm wheel 74 which is mounted upon a transversely 25 extending shaft 75 mounted in front and rear brackets 76 and 77 of the frame 67. A worm gear 78 is mounted upon the shaft 75 and is in mesh with a worm wheel 79 carried by the cam shaft 80. The cam shaft 80 is provided with cam discs 81 30 and 82. These discs are spaced in relation to each other upon the shaft 80 and are each formed with a cam groove in their opposing faces. The cam groove represents a single throw cam and as is shown in Fig. 4 of the drawings, the throw of 35 these cams are angularly spaced from each other for a purpose to be hereinafter described. A rock shaft 83 is mounted through the uprights 68 and 69 of the frame 67 and carries an operating lever 84 upon which a roller 85 is mounted. The roller 40 engages the cam groove of the cam 82 and is directly concerned with the tilting of the popcorn receptacle 21. The lever 84 is pinned to the shaft 83 and rotates therewith. Freely mounted upon the shaft 83 is a bell crank 86 having an upwardly 45 projecting arm 87 which connects with the operating link 59 of the feed valve. The bell crank 86 has a lever 88 which carries a roller 89 and meshes with the cam groove of the cam disc 81, thus the bell crank may rock upon the shaft 83 50 independently of rotation of the shaft as actuated by its lever 84. Fixed to the end of the shaft 83 is a lever 90. This lever extends downwardly and carries a pivot pin 91 to which the tilt bar 45 is connected as previously described.

55 Fixed upon the shaft 83 is a pump lever 92 which carries a pump rod 93 extending downwardly into the popping oil reservoir 25. Mounted upon the lower end of the pump rod is a piston 95 here shown as being circular in shape and having a reduced lower end portion 96 to provide clearance at the bottom of the piston for a purpose to be hereinafter described. The piston reciprocates within a cylinder 97 mounted within the reservoir having a communicating port 98 65 to permit fluid to be drawn into the reservoir. Adjacent to the lower end of the cylinder 97 there is an outlet pipe 99 which extends upwardly and over the lip of the heating pan 30 previously described. On the down stroke of the pump a 70 considerable quantity of popping oil is forced upwardly through the tube 99 and into the heating pan, and on the reverse stroke such oil as is represented by the depth of submergence of the down turned mouth 100 of the tube will be 75

drawn back into the reservoir. This tends to maintain the oil clean and sweet and at the same time will insure that a constant level of oil will be maintained above the heating elements within the pan 30.

Vibration of the popping receptacle 31, as has been previously indicated, is produced by rotation of the cam element 73 as it moves against the end of the vibrating rod 48, and this in turn acts against the end of the receptacle. The receptacle 31 has limited movement upon the horizontal portion of the arms 40 due to the fact that slotted openings 101 are formed in the arms to receive fastening pins 102. Attached to one of the fastening pins 102 on each side of the receptacle is a spring 103 which is attached to a pin 104 carried by the arm. This makes it possible for the receptacle to have a limited horizontal movement with relation to the tilting arms 40 and while being vibrated by the rod 49. Supporting stops 104 are mounted upon the base structure associated with the heating pan 30 and thus insure a rigid support for the heating receptacle while it is being horizontally vibrated.

The vibrating action in the present instance also performs the function of measuring a desired quantity of salt to be supplied to the batch of popcorn as it is being discharged from the receptacle. The salt supplying device comprises a box 105 which is detachably mounted upon the horizontal portion of the top wall 34 of the popping receptacle and may be secured by an angular member 106 and a pin 107. A bottom wall is formed in the salt container as indicated at 108. A false top wall 109, is disposed thereabove and forms a throat 110 therebetween. The top wall terminates short of the rear of the container and is there formed with an upwardly extending lip 111 which forms one marginal edge of a passageway 112 establishing communication from the container 105 to the passageway 110. As the receptacle vibrates a small amount of salt will shake over the lip 111 and through the passageway 112 into the lower passageway 110 from which it will be emptied when the receptacle is tilted through opening 113 formed in the upper wall 34 of the popping receptacle 21.

As hereto before stated, the present invention is intended preferably as a coin controlled popcorn dispensing device in which the corn actually popped after a coin has been inserted will be dispensed to the purchaser. For that purpose a conventional type of coin control is utilized as generally indicated at 114 in the drawings. This device comprises a housing 115 mounted through the front wall of the case and slidably supporting an operating bar 116. A coin is placed in the opening 117 and when so placed will permit the operating bar to slide rearwardly and actuate the switch mechanism with which the structure here disclosed is provided. Referring more particularly to Figs. 8, 9 and 10 of the drawings it will be seen that the switch mechanism includes a frame 118 within which a shaft 119 is rotatably mounted. This shaft projects through vertical members 120 of the frame which are spaced from each other. At one end of the shaft is an adjusting arm 121 which may be set upon the shaft in a desired angular position by a set screw 122. The limit of rotation of the shaft and arm 121 is adjustably controlled by a lug 123 and a set screw 124. Mounted upon the opposite end of the shaft 119 is a friction collar 125 which is pinned to the shaft and against which a face of an operating lever 126 is held yieldably by a coil

spring 127 which circumscribes the shaft 119 and is set with a desired tension by nuts 128. The lever 126 is attached to an operating link 129 by a pivot pin 130. The upper end of the link 129 is attached by a pivot pin 131 to a lever arm 132 which is mounted in an adjustable set position upon the pivot rod 42 by a set screw 133. This particular arrangement is shown in Fig. 10 of the drawings.

Mounted upon the shaft 119 are two switch levers 134 and 135. The switch lever 134 has an upwardly extending arm 136 and a downwardly extending arm 137. The switch lever 135 has an upwardly extending arm 138 and a downwardly extending arm 139. The downwardly extending arm 137 carries a mercury switch tube 140 and the downwardly extending arm 139 carries a mercury switch tube 141. One of these tubes is disposed at an angle to the radius of its supporting arm, and the other tube is disposed at an opposite angle to the radius to its supporting arm for a purpose to be hereinafter described. The lever 134 is freely mounted upon the shaft 119 and is urged toward its normal position with the arm 136 extending forwardly as acted upon by a spring 142. The switch arm 135 is partially free to rotate upon the shaft 119 and will snap from one position to another as actuated. The hub of the switch arm 135 indicated at 143 is formed with a cut-away segment 144 into which a pin 145 extends. This pin is fixed radially upon the shaft 119. A frame structure 146 is pivotally secured on a pin 147 to the arm 138 and is attached at its lower end to a spring 148 which in turn is suitably fastened to the bottom of the frame structure. Thus when the upper end of the arm 138 is swung over center by force applied by the coin operating mechanism it will retain this position until the pin 145 engages the side of the segment 144 at which time it will be urged to rotate toward its normal position and when it passes over center the spring 148 will instantly pull it to its original position preparatory to actuation by the coin control mechanism. It is to be understood that the upper arm members 136 and 138 lie in the path of travel of the coin operated bar 116 and that they will both be swung to their extreme positions as the bar moves inwardly after which the arm 136 will move back to its original position under influence of the spring 142.

As shown in the drawings, two forms of wiring diagram and thermostat control are provided. One showing the use of an electric thermostat disclosed in Fig. 11, and the other being by the use of a fluid pressure thermostat as shown in Fig. 12. Referring particularly to Fig. 11 of the drawings it will be seen that lead wires 150 and 151 are provided. A storage heater 152 which is mounted within the oil reservoir unit 25 is directly connected to the leads by wires 153 and 154. A conductor 155 leads to one side of a mercury tube 140, which tube is provided with a conductor 156 leading to mercury tube 141, the two tubes being connected in series. A conductor 157 connects the tube 141 with the motor 23. A lead conductor 158 completes the motor circuit. The heating element lead wires 28 and 29, as previously described, supply current to a plurality of heating elements 27. The lead wires 28 and 29 connect folds of a double knife switch having blades 159 and 160. These make contact with the conductors 150 and 151. The switch is controlled by a relay 161 having a conductor 162 connected with the lead wire 150 and a con-

ductor 163 which is broken by a switch element 164. The switch element 164 is controlled by a suitable thermostat 165 which is submerged within the heating oil and controls the heat of the oil at a predetermined temperature within the pan 30.

In the form of the invention shown in Fig. 12 of the drawings, the wire diagram is substantially the same as previously described, but a pressure control device is shown for the heater. In this form of the device a fluid tube 166 is submerged within the oil in the pan 30 and provided with a conduit 167 which leads to a siphon bellows 168. This bellows when extended operates the blades 159 and 160 of the two-way switch previously described. Across the corresponding line terminals of this switch condensers 169 and 170 are placed.

It has been found that during the tilting operation there is a tendency for oil from the pan to adhere to the floor pan by capillary attraction and to drain toward the lower end of the floor when the receptacle is tilted. In order to prevent this from draining over the edge of the pan 30 a drain member 171 is provided. This member is in the form of a thin metal plate which is hinged at 172 to the forward edge of the receptacle. The trailing edge of the plate is preferably reduced in width, but in any event the material which drains downwardly along the floor of the receptacle will encounter the plate 171 and will then drain oppositely back into the body of oil within the pan 30 rather than to drain over the side of the pan and on to unrelated parts.

In the operation of the present invention the popcorn receptacle 24 is suitably filled with popcorn and the adjusting plate 56 in the shute 55 is adjusted to control a space 58 through which the corn may flow to the measuring element 59. This element being semi-cylindrical receives the popcorn and delivers it to the outlet spout 51 which is controlled by the gate 60. It will be understood that it might be possible to operate the device by eliminating the gate 60 if desired. When it is used, however, the roller 64 on the lever arm 63 will bear against the rear wall of the popping receptacle 24 and will hold the gate open, but will act as a safety device to close the spout automatically while the popping receptacle is tilted. The reservoir 25 which receives the popping oil has been filled as well as the heating pan 30. When the current is initially turned on in the machine it will directly flow to the storage heater 152 which is located within the popping oil reservoir 25. This will maintain the popping oil at a suitable temperature at all times. The machine may then be placed into operation by placing a coin in the opening 117 of the coin housing 115 and then moving the operating bar 116 in the direction of the arrow as shown in Fig. 3 of the drawings. The rear end of the operating bar 116 when moved a sufficient distance rearwardly will encounter the upwardly extending and forwardly leaning arms 136 and 137 of the switch levers 134 and 135 respectively. These levers as shown in Fig. 8 of the drawings will simultaneously swing in the direction of the arrow "b" and will at the same time incline the mercury switch tubes 140 and 141 to assume the positions indicated in dotted lines in Fig. 8. When the operating bar 116 is retracted the switch lever 134 will be restored to its original position by the spring 142 so that the tube 141 carried thereby will be disposed at an angle

to complete a circuit in series through the two tubes 140 and 141. The motor may be controlled by a rheostat 190. This is mounted in the line 157 to the motor and a circuit will thus be completed from the lead wire 151 through conductor 155, the tubes 140 and 141 and their intermediate conductor 156 and thence along conductor 157 and the rheostat to the motor 23. The circuit is completed from the motor along conductor 158 to lead wire 150.

A circuit will be partially established to the heating elements 27 of the pan 30 from conductor 150 and conductor 151 to the switch elements 159 and 160 and thence along conductors 28 and 29 to the heating elements. This circuit is completed when the oil is below a predetermined temperature and the switch elements 159 and 160 are closed by the relay 161 as actuated by the thermostat 165. When a predetermined set temperature is reached the thermostat will release the relay and the switch elements 159 and 160 and will move to interrupt the circuit. As previously described in the form of the device shown in Fig. 12 of the drawings, the expansion of the heating liquid in the tube 166 will cause expansion of the siphon bellows 168 and will break the circuit to the heating elements 27. In either event it will be evident that a constant control temperature of the heating oil will be maintained. When the switch levers 134 and 135 assume the position shown in Fig. 9 of the drawings they will establish the motor circuit as previously described and the sequence of the operation of the machine will then proceed. The motor will drive the shaft 71 through the transmission unit 70 and will cause the worm gear 72 to drive the worm wheel 74. This in turn will rotate shaft 75 with its worm gear 78 and will rotate the operating cams 81 and 82 in the direction of the arrow "c" as shown in Fig. 4 of the drawings. The operating cam 81 which is engaged by the roller 89 carried by the arm 88 of the lever 86 will swing the lever arm 87 forwardly in the direction of the arrow "d" in Fig. 2, and this in turn will rotate the popcorn measuring valve 53 forwardly until it discharges a measured amount of popcorn in the open throat 51. The popcorn will then pass directly through the opening 50 in to the top of the receptacle and will rest upon the bottom wall 35 of the receptacle. It will be understood that at this time the bottom wall of the receptacle is submerged to a predetermined depth within the popping oil carried by the pan 30. As the cam 81 continues to rotate it will swing the lever arm 86 so that the operating connecting rod 59 will restore the popcorn measuring valve to its original position. The shaft 71 which is continuously rotating will revolve its cam 73 acting to vibrate the rod 48 and to thus impart a horizontal vibrating motion to the popping receptacle 31 as it is supported on the arm structure 40. The springs 103 will hold the popcorn receptacle yieldably with its member 49 against the vibrating rod 48. During this period the popping operation takes place. At the same time the salt receptacle 105 is vibrating so that small quantities of salt will be shaken over the lip 111 through the passageway 112 and into the throat 110 preparatory to being discharged therefrom when the popping operation has been completed. As the cam shaft 80 rotates the cam disc 82 will move the roller 85 and swing the rocker arm 84 which is pinned to the shaft 83. This will cause the lever 90 to swing in the direction of the ar-

row "d" as indicated in Fig. 2, and will act to direct the draw bar 45 to swing the lever structures upwardly and forwardly as indicated at "e" in Fig. 2. This will lift the popping receptacle 31 upwardly from the heating pan 30 and will swing it forwardly to tilt it between the confining side members 36. At the same time the salt receptacle will be inclined and cause salt to pour through the throat 110 and to sprinkle down upon the falling popcorn. The salted popcorn will then pass into the throat 37 where it accumulates upon the gate 39. This gate may be opened at the will of the operator by pulling upon an operating knob 191 carried upon a rod 192 and extended through the cover panel 15 to lever 193 which is pivoted upon a pin 194. A counterweight arm 195 is formed integral with the lever 193 and carries a counterweight 196. The gate 139 is secured to this structure and will swing downwardly to open the throat 37 when the rod 192 is drawn forwardly. Conveniently disposed within the machine, such for example at 197, is a receptacle carrying sacks which may be withdrawn to receive the popcorn discharged through the chute 38.

Attention is directed to the fact that at the time the popping receptacle is tilted and swings around the axis of the shaft 42 it will cause lever 132 to swing downwardly as indicated by the arrow "f" in Fig. 5 of the drawings. This will operate the arm 126 which frictionally engages the switch shaft 119 and as the shaft 119 is thereby rotated the pin 145 carried by the shaft 119 will engage the face of the cut-away segment 144 on the boss 143 of switch lever 135 and cause it to swing in a counter-direction to that indicated by the arrow "b" in Fig. 8 so that as the lever passes over center the spring 148 will swing the lever 135 to a position of alignment with the lever 134. During this swinging movement the motor circuit will be broken and when the popping receptacle is restored to its normal horizontal position the lever arm 126 will be returned to its original position ready for the next operation. As the shaft 83 rotates on its axis it also swings the pump lever 92. This swinging action takes place as the popping receptacle 31 is raised and tilted to discharge its contents. While the swinging action takes place the piston rod 93 is forced downwardly and then outwardly and upwardly through the tube 99. This action will supply an excess of popping oil to the pan 30, but when the cycle of operation continues the piston 95 will be lifted within the cylinder 97 and will draw oil back into the reservoir 25 until it has been lowered to the level of the down turned lip 100 of the tube 99, at which level it will be maintained.

It will thus be seen that the invention here disclosed provides a simple and effective means for measuring, popping and dispensing popcorn by an automatic operation set into action by a coin control mechanism and following through its sequence of performance without the further attention of an operator. It will also be manifested that by submerging the perforate floor of the popping receptacle into a controlled quantity of popping oil the corn will be initially submerged within the oil and will subsequently pop in a relative short interval of time and will require a desirable degree of freshness and flavor as the operation proceeds. It will be evident that these operations are brought about without possibility of fire hazard and without necessity

of popping large batches of popcorn in anticipation of the demands of customers.

While I have shown the preferred form of my invention as now known to me, it will be understood that various changes may be made in combination, construction, and arrangement of parts by skilled in the art, without departing from the spirit of my invention as claimed.

Having thus described my invention, what I claim and desire to secure by Letters Patent is:

1. In a machine for popping popcorn and vending the same, comprising a heating pan containing a quantity of popping liquid, electric heating means associated with said pan for heating the liquid, a separate popping liquid reservoir, and operating means acting to fill the heating pan with liquid in excess of that required for the popping operation and to thereafter withdraw liquid from the pan until a predetermined level is reached.

2. In a machine for popping popcorn and vending the same, comprising a heating pan containing a quantity of popping liquid, electric heating means associated with said pan for heating the liquid, a separate popping liquid reservoir, operating means acting to fill the heating pan with liquid in excess of that required for the popping operation and to thereafter withdraw liquid from the pan until a predetermined level is reached, and means for heating the liquid within the reservoir.

3. A machine for popping and vending popcorn, comprising a heating pan into which popping oil is placed, electric heating means therefor, a popping oil reservoir, an electric heating element within said reservoir, a reciprocating pump adapted to be actuated to deliver a surplus amount of popping oil from the reservoir to the heating pan on its stroke in one direction and to withdraw an excess amount of oil from the heating pan on its stroke in the opposite direction, switch means for establishing electric circuits through said heating element, mechanical means for operating said pump, and means associated therewith for opening the switch at the conclusion of the pump stroke to deliver popping oil from the reservoir to the heating pan.

4. A machine for popping and vending popcorn, including an enclosure, a popcorn spout leading through a wall thereof, a coin control device mounted through a wall thereof, a heating pan disposed within said enclosure, electric heating elements positioned within the bottom of said pan, a popping oil reservoir, a reciprocating pump delivering oil from the reservoir to the pan on one stroke and returning surplus oil to the reservoir on the opposite stroke, a tiltable popping receptacle having a discharge opening in the side thereof, and a foraminated floor in the bottom thereof, means for supporting said tiltable receptacle to permit it to swing from a position where its floor will be submerged in the popping oil within the heating pan and whereby it may be lifted and swung to an inclined position to cause popped corn to be discharged through the open side thereof and into the chute through the wall of the enclosure, a corn hopper, measuring means for delivering a determined quantity of corn to the receptacle for popping, an electric motor, synchronous operating means driven thereby, said synchronous operating means actuating the pump, the tilting receptacle and the corn measuring means in a popping cycle, and an electric circuit for the popping oil heating means, an electric circuit for the motor, and a switch actuated

by the coin control means for closing said circuits and actuated by the synchronous driving means at the conclusion of the popping cycle to open said circuits.

- 5 5. A machine for popping and vending popcorn, including an enclosure, a popcorn spout leading through a wall thereof, a coin control device mounted through a wall thereof, a heating pan disposed within said enclosure, electric heating 10 elements positioned within the bottom of said pan, a popping oil reservoir, a reciprocating pump delivering oil from the reservoir to the pan on one stroke and returning surplus oil to the reservoir on the opposite stroke, a tiltable popping receptacle having a discharge opening in the side thereof, and a foraminated floor in the bottom thereof, means for supporting said tiltable receptacle to permit it to swing from a position where its floor will be submerged in the popping oil within the 15 heating pan and whereby it may be lifted and swung to an inclined position to cause popped

corn to be discharged through the open side thereof and into the chute through the wall of the enclosure, a corn hopper, measuring means for delivering a determined quantity of corn to the receptacle for popping, an electric motor, synchronous operating means driven thereby, said synchronous operating means actuating the pump, the tilting receptacle and the corn measuring means in a popping cycle, an electric circuit for the motor, a switch actuated by the coin control 10 means for closing said circuits and actuated by the synchronous driving means at the conclusion of the popping cycle to open said circuits, means permitting limited movement between the popping receptacle and its support, and vibrating means 15 driven by said synchronous driving mechanism when the popping receptacle is in its popping position whereby to vibrate the receptacle with relation to its support.
